(57) **CLAIM**

The ornamental design for a ceiling fan, as shown and described.

DESCRIPTION

FIG. 1 is a bottom, front, left perspective view of a first embodiment of the ceiling fan showing my new design; FIG. 2 is a top, front, left perspective view thereof; FIG. 3 is a top plan view thereof; FIG. 4 is a bottom plan view thereof; FIG. 5 is a left side elevation view thereof; FIG. 6 is a right side elevation view thereof; FIG. 7 is a front elevation view thereof; FIG. 8 is a rear elevation view thereof; FIG. 9 is an enlarged view of the section shown in FIG. 2; FIG. 10 is an enlarged view of the section shown in FIG. 3. FIG. 11 is a bottom, front, left perspective view of a second embodiment of the ceiling fan showing my new design; FIG. 12 is a top, front, left perspective view thereof; FIG. 13 is a top plan view thereof; FIG. 14 is a bottom plan view thereof; FIG. 15 is a left side elevation view thereof; FIG. 16 is a right side elevation view thereof; FIG. 17 is a front elevation view thereof; FIG. 18 is a rear elevation view thereof; FIG. 19 is an enlarged view of the section shown in FIG. 12; and,

FIG. 20 is an enlarged view of the section shown in FIG. 13. The broken line showing with uniform dashes in the figures is for the purpose of illustrating portions of the ceiling fan and forms no part of the claimed design. The broken line showing with dots-and-dashes in the figures is for illustrating an imaginary boundary line and forms no part of the claimed design.
